UNITED STATES PATENT OFFICE.

JOHN C. KEARNS, OF MAITLAND, PENNSYLVANIA.

PRUNING IMPLEMENT.

SPECIFICATION forming part of Letters Patent No. 746,964, dated December 15, 1903.

Application filed June 26, 1903. Serial No. 163,276. (No model.)

To all whom it may concern:

Be it known that I, JOHN C. KEARNS, a citizen of the United States, residing at Maitland, in the county of Mifflin and State of Pennsylvania, have invented certain new and useful Improvements in Pruning Implements; and I do hereby declare the following to be a full, clear, and exact description of the invention, such as will enable others skilled in the art to which it appertains to make and use the same.

My invention relates to certain improvements in pruning implements.

It consists of the construction and arrangement of parts hereinafter described, and more particularly pointed out in the claims.

In the accompanying drawings, illustrating the preferred embodiment of my invention, Figure 1 is a side view of my improved pruning-hook with part of the staff broken away. Fig. 2 is an enlarged detail view of the hook and knife. Fig. 3 is an edge view of the same. Fig. 4 is an enlarged cross-sectional view, taken on the line $x-x$ of Fig. 1. Fig. 5 is a longitudinal sectional view of the knife, showing its tapering form and its connection to the operating-rod; and Fig. 6 is an enlarged detail edge view of the bracket and lever.

Referring more particularly to the drawings, 1 is the hook, which, contrary to the usual custom, curves upwardly from the stock, which is preferably secured by bolts or other suitable means to the staff 2. Said staff is provided with a suitable handle 3 upon its opposite end. Said hook has a slot or way 1^a therethrough, in which is adapted to move the knife 4, which tapers laterally and longitudinally toward the upper and lateral cutting edges 4^a and 4^b, respectively. The knife is 35 suitably attached to the operating-rod 5, which is provided at its upper end with a stop 5^a, which limits the downward movement of the knife. The hook 1 has a lateral way 1^b, in which the upper end of the operating-rod 40 works and which confines it in position avoiding contact of the cutting edge of the knife with the hook. Said knife is preferably serrated near the cutting edge 4^b to prevent slipping upon the wood while cutting and 45 also to prevent the knife binding in the cut or kerf of the wood. The other extremity of

the operating-rod 5 is attached to the lever 6, preferably on either side of the bracket 7, which is secured by screws or other suitable means to the staff 2. Said bracket has two 55 extending sides 7^a and 7^b, each having a longitudinal slot 7^c, in which work the ends of the bolt 8, passing through the lever 6 and engaging the end of the operating-rod. Along the inner surface of the bracket is a series of 60 ratchet teeth or cogs 7^d. The lever 6 is fan-shaped at its engaging end and has teeth or cogs 6^a meshing with those carried by the bracket. In connecting the operating-rod to the lever said rod is offset at 5^b a short distance above said bracket, and a piece of the same material is riveted or otherwise secured immediately above this offset portion and has an offset in the opposite direction, the rod and the piece secured thereto extending down on 70 opposite sides of the bracket and engaging the opposite ends of the bolt 8.

The upper cutting edge 4^a of the knife may be used for trimming or cutting small branches or twigs from the trunks or larger 75 branches by using the tool with an upward jabbing motion.

Other advantages of my implement are that there is a straight pull on the knife by the lever through the operating-rod, the geared 80 connection between the lever and the bracket does away with all jerking motion and greatly lessens the labor necessary in operating the tool, and the hook curving upwardly is in the best possible position to accomplish the best 85 results.

It is to be understood that I do not limit myself to the details of construction described herein, as they may be varied at will and the spirit of my invention remain intact and be 90 protected.

Having thus described my invention, what I claim as new, and desire to secure by Letters Patent, is—

1. In a device of the character described, 95 the combination of a staff, a hook, a knife, a rod connected at one end to said knife, a bracket, having cogs, secured to said staff, a lever having cogs meshing with the cogs of said bracket and means for connecting said 100 rod to said lever.

2. As a new article of manufacture, a de-

vice of the character described comprising a staff having a handle at one end, an upwardly-projecting hook secured to the other end, a knife having a substantially horizontal cutting edge and an inclined serrated cutting edge, a stop limiting the downward movement of said knife, an operating-rod connected at one end to said knife and a lever, connected to the other end of said operating-rod, having

gear connection with a bracket secured to said staff, substantially as set forth.

In testimony whereof I affix my signature in presence of two witnesses.

JOHN C. KEARNS.
